J. C. HARPHAM

HARNESS ROSETTE

Filed Sept. 9, 1922

Fig. 3.

Inventor

J. C. Harpham.

By

Lucy Dailey, Attorneys

UNITED STATES PATENT OFFICE.

JULIUS C. HARPHAM, OF LINCOLN, NEBRASKA.

HARNESS ROSETTE.

Application filed September 9, 1922. Serial No. 587,156.

To all whom it may concern:

Be it known that I, JULIUS C. HARPHAM, a citizen of the United States, residing at Lincoln, in the county of Lancaster and State of Nebraska, have invented certain new and useful Improvements in Harness Rosettes, of which the following is a specification.

This invention relates to harness rosettes and has special reference to devices for connecting the several straps of a bridle. The object of the invention is to provide a simple, inexpensive, compact and attractive device which will effectually hold the parts of the bridle together and will impart an ornamental appearance thereto. The invention is illustrated in the accompanying drawings and will be hereinafter fully set forth and defined.

20 In the drawings—

Figure 1 is an elevation of my improved rosette applied to a bridle;

Fig. 2 is a detail section of the rosette on the line 2—2 of Fig. 1, and

25 Fig. 3 is a bottom plan view of the rosette.

In carrying out my invention, I employ a base ring or loop 1 which may be of the exact form shown in the drawings having one square end 2 and one round end 3 connected by straight parallel sides, or may be of a circular or elliptical outline. The parallel side members are connected adjacent their ends by cross bars 4 and from the base ring or loop two or more posts 5 rise 30 to carry a top ring 6 which is preferably of an elliptical outline, as shown. Over the top ring 6 is fitted a sheet metal cap or top plate 7 which is of the same outline as the said ring 6 and has its edge rolled over and 35 under the edge of the said ring, as shown at 8.

In applying the rosette to a bridle, the under enlarged end 9 of the crown piece 10 is disposed below the rosette with the 40 rosette disposed with its major diameter transverse to the crown piece, and the attaching strap 11 of the crown piece is passed around the upper side bar of the base ring 1 and buckled so as to be retained in en-

gagement therewith. The cheek strap 12 50 may be passed around the opposite side bar of the base loop and fastened by a buckle, but is preferably stitched, as indicated at 13. The throat latch 14 is secured around the end member 3 of the base ring in the 55 same manner that the cheek strap 12 is secured, and the brow band 15 is in a similar manner secured around the end bar 2 of the base ring. The cross bars 4 are so located that, when the cheek strap and the 60 crown piece are engaged with the base ring, movement of said members along the sides of the base ring will be prevented and the width of the ring is such that the side members thereof will prevent lateral movement 65 of the throat latch and the brow band. The base ring, cross bars, posts, and top ring are preferably formed integrally by casting and while I have indicated four posts in the accompanying drawings, it will be understood 70 that two posts may be sufficient. The sheet metal top or cap plate 7 may be flat or nearly so and may be engraved or otherwise embellished so as to enhance the attractiveness of the device, while the enlarged end 9 of 75 the under member of the crown piece serves to maintain the base ring and the parts engaged therewith from contact with the head of the animal and thereby prevents irritation with resulting soreness. My improved rosette is exceedingly simple in construction, may be produced at a low cost 80 and may be easily applied to any bridle and, when applied, will effectually retain the several straps of the bridle in proper relation. 85

Having thus described the invention, what is claimed as new is:

A harness rosette comprising a base loop of elongated form having cross bars formed integral therewith adjacent its ends, posts rising from said base loop and integral therewith, a top ring carried by said posts and integral therewith, and a sheet metal cap plate fitted over the top ring and having its edge rolled over and under the edge of 90 said top ring.

In testimony whereof I affix my signature.

JULIUS C. HARPHAM. [L. s.]
